SOL L. BUSCHMAN, OF NEW YORK, N. Y., ASSIGNOR TO METAL PACKAGE CORPORATION OF NEW YORK, OF NEW YORK, N. Y., A CORPORATION OF NEW YORK.

CLOSURE FOR CONTAINERS.

Application filed May 2, 1924. Serial No. 710,498.

My invention relates to closures or caps for closing bottles or other containers and in an air-tight manner and it is adapted in its application to supersede the well-known 5 crown cap which is applied and held to the bottle by a tool which bends or turns the lower edge of the flange of the cap under an annular bead on the upper end of the neck of the bottle and which must be removed by a special opener.

Although it is not to be so limited in its application the invention is peculiarly adapted for closing and sealing bottles or other containers containing a charged or effervescent water or other liquid. It is superior to the caps heretofore used for that purpose inasmuch as it may be applied manually and after it has been removed it may readily be replaced manually on the neck 20 of the bottle and it will then function just as effectively as it did on its first application.

Further objects and advantages of the invention will appear from the accompanying description, the invention consisting in the novel closure hereinafter more particularly described and then specified in the claim.

In the accompanying drawing illustrating 30 a practical embodiment of the invention:

Fig. 1 is a side elevation (partly in section) of the neck of a bottle showing the closure in section before it is screwed into closing or air-tight position.

Fig. 2 is a similar view showing the position of the closure after it has been screwed "home" or into closing position.

Fig. 3 is a plan view of the cap.

Referring in detail to the several figures 40 of the drawing:

1 indicates a bottle which may be of glass or any other material and which is provided with a neck 2 which is exteriorly screw-threaded as illustrated. 3 indicates the upper wall of a metallic closure or cap, said cap being provided with a downwardly depending annular flange 4 which is interiorly screw-threaded and which is adapted to be screwed on the neck 2. The upper wall 3 is provided with an annular depression or inverted bead 5 which is positioned adjacent the inner wall of the mouth of the bottle when the cap is screwed on the neck. The upper wall 3 is also provided with a

central annular and indented portion 6 extending downwardly below the surface of said wall.

The formation of the depressed bead 5 results in inner and outer upwardly inclined portions, the former cooperating with the 60 indented portion 6 to resist upward or inward movement of the bead 5 when it is compressed against the material forming the neck 2 of the receptacle 1. 7 indicates a flat washer preferably of more or less pliable 65 or flexible cork, the composition thereof having qualities permitting it to retain a different configuration or shape after it has been deformed by pressure applied thereto. Said washer fits snugly and is frictionally held 70 within the cap and engages the inner wall thereof as well as the inverted bead or depression 5.

When the cap is applied to the neck of the bottle and is screwed down tightly 75 thereon into the position shown in Fig. 2 the configuration of the cork washer 7 will be deformed so as to follow the contour of the upper wall 3, the inverted bead 5, and the indentation 6 as clearly shown in Fig. 80 2 and that portion of the washer adjacent its periphery will be clamped against the edges of the neck of the bottle by that portion of the upper wall 3 adjacent its periphery. Those portions of the cork which engage the indentation 6 and inverted bead 5 will be forced within the mouth of the bottle, the inverted bead 5 acting also to jam the washer firmly and securely against the periphery of the edge of the mouth of 85 90 the neck of the bottle to provide an air-tight closure.

When it is desired to use the contents of the bottle or container it is merely necessary to unscrew and remove the cap, the cork 95 meanwhile being frictionally held within the cap and retaining the configuration into which it has been deformed. When sufficient amount of the contents of the bottle has been used the cap may again be applied 100 to and screwed firmly on the neck whereupon it will again act as an air-tight closure for the bottle or container.

What I claim as my invention is:—

A closure for receptacles having a screw-threaded neck and comprising a cap provided with an upper wall and with a depending screw-threaded annular flange

adapted to be screwed on said neck, said upper wall including an inturned circular bead formed by inner and outer upwardly inclined circular portions, said bead being positioned adjacent to the material forming the neck of said receptacle when said cap is screwed thereon and a flexible disk with-

in said cap and compressible between said bead and the neck of said receptacle.

Signed at New York in the county of ¹⁰ New York and State of New York this 26th day of April, A. D. 1924.

SOL L. BUSCHMAN.
